CLAIM

The ornamental design for a photograph display stand, as shown and described.

DESCRIPTION

FIG. 1 is a front elevational view of a photographic display stand showing my new design;

FIG. 2 is a right side elevational view thereof;

FIG. 3 is a top plan view thereof;

FIG. 4 is a bottom plan view thereof;

FIG. 5 is a right side elevational view thereof showing the display members in a transitory position;

FIG. 6 is a front elevational view of a modified form of the design shown in FIG. 1;

FIG. 7 is a right side elevational view thereof;

FIG. 8 is a top plan view thereof;

FIG. 9 is a bottom plan view thereof; and

FIG. 10 is a right side elevational view thereof showing the display members in a transitory position.

The left side elevational view for each embodiment is substantially the same as the right side elevational view shown in FIGS. 2 and 7.
